UNITED STATES PATENT OFFICE.

IRA W. FOLTZ, OF CHICAGO, ILLINOIS.

FURNACE.

1,322,183.

Specification of Letters Patent. Patented Nov. 18, 1919.

Application filed January 29, 1917. Serial No. 145,184.

To all whom it may concern:

Be it known that I, IRA W. FOLTZ, a citizen of the United States of America, and a resident of Chicago, county of Cook, and State of Illinois, have invented certain new and useful Improvements in Furnaces, of which the following is a specification.

This invention relates to air heating appliances for furnaces and is an improvement 10 on a similar appliance disclosed in applicant's copending application for patent on furnaces, Serial No. 82,414, filed March 6, 1916.

The objects of the invention are to provide improved means whereby the air which supports secondary combustion may be supplied through the furnace with the air which supports primary combustion, or may be supplied independently of the air which 20 supports primary combustion; and to provide improved means for cleaning the secondary air supply appliance.

An illustrative embodiment of this invention is shown in the accompanying drawings, in which—

Figure 1 is a side elevation with the masonry in section of a furnace provided with the present improvements, and taken on line 1—1 of Fig. 2.

Fig. 2 is a transverse vertical section taken on the line A—A of Fig. 1.

Fig. 3 is a sectional plan view taken on the line E—E of Fig. 1.

Fig. 4 is a detail, partly in section, taken 35 on the line 4—4 of Fig. 1, showing one of the adjustable doors for controlling an air inlet of the air supply conduits.

It has been to some extent recognized in this art that better results may be obtained 40 in the combustion of solid fuel such as coal if, instead of permitting the entire air supply to pass through the fuel body, a separate or secondary supply of heated air be provided for the gases arising from the fuel 45 and then the mixture of gases and air conducted to a region of fire and flame that will cause their complete ignition. If all the air supplied to the furnace is permitted to enter the same at the ash-pit in a comparatively 50 cold state, and then to pass through the solid fuel, it may support a lively initial combustion of the solid matter of the fuel while the gases which are distilled from the solid fuel may pass off unburned because of lack of sufficient heat to 55 ignite them, that is, there may be air suffi-

cient in quantity but of too low temperature to insure the ignition of the distillates. It is therefore difficult, under such conditions, to obtain good results in the burning of fuel irrespective of the quantity of fuel consumed in a given time.

Various appliances have been proposed to provide means in furnaces for heating air which is independently supplied to the firebox above the fuel body or to the combustion chamber. Such appliances frequently require considerable alteration to be made in standard forms of furnaces when installed therein. Also, when such appliances were made of a good heat conducting material such as iron, they would rapidly deteriorate if so located in the furnace as to be subject to the effects of high temperatures occurring therein.

In the present case, the air heating appliances extend along the boiler in order that the latter may have some cooling effect on said appliances and prevent the burning of the same while said appliances are still properly located and operate satisfactorily in conducting the required heat to the air passing through the appliances.

The drawings show a return draft tubular type of furnace wherein the boiler 1 is suspended by yokes 2 depending from transverse I-beams 3 in turn supported on the vertical pillars 4. The masonry 5 which surrounds the boiler and forms the combustion chamber 6, the fire-box 7 and ash-pit 8 is preferably formed to provide a plurality of alternately restricted and enlarged passages in the combustion chamber for the purpose of causing eddy currents to insure good mixture of the air and gases passing through the furnace, and also to retard the flow of the same to allow sufficient time for complete combustion. This is accomplished by means of the usual bridge wall 9 at the rear of the grate 10 and extending upwardly 90 toward the boiler. A transverse wall 11 extends across the combustion chamber at the rear of the bridge wall and is provided with a central opening 12. Still farther to the rear and in line with opening 12 is a pillar 13 formed as shown in Fig. 3, which normally provides a heated surface 14 against which the gases impinge after passing through the opening 12. At the rear of the grate and somewhat forward of the bridge wall 9 is a transversely extending arch or baffle 15 which is supported by the side walls

of the furnace and a central pillar 16 being formed to provide passages 17 therethrough from the fire-box or grate region to the combustion chamber. The arch 15 also is 5 provided with vertical passages 18 having inlets 19 at the upper part of the fire-box and outlets 20 immediately to the rear of the fuel body 21 on grate 10.

This arrangement of baffle or arch at the 10 rear of the fire-box, together with the fire-box lining, provides a more or less enclosed space within which gases may collect which arise from the fuel body 21. These 15 gases are conducted from said space through the vertical channels 18 to the flame which normally sweeps by the outlets 20 of said passages from the burning fuel into the combustion chamber.

The improved means for supplying heated 20 air to the fire-box above the fuel body comprises conduits 22 having inlets 23 in the ash-pit and from there leading upwardly through the side walls 24 to horizontal conduits 25 located in proximity to the boiler 25 and extending from the front to the rear end of the furnace. The conduits 25 also extend through the front wall 26 where they are provided with additional air inlets 27. The air inlets 27 are controlled by hinged 30 doors 28. At the rear end of the furnace, conduits 25 are connected with similarly formed return conduits 29 by an elbow 30. The conduits 29 also pass through the front wall 26 of the furnace, and the open ends 35 thereof are controlled by doors 31. The conduits 29 communicate with branch conduits 32 which provide outlets 33 in the upper part of the fire-box above each of the firing doors 34.

40 By the present arrangement of air heating conduits, the same may be installed in furnaces of the general type shown without much alteration thereof, and while properly located to insure a sufficient supply of heated 45 air for supporting secondary combustion, are not subject to the excessive temperatures which occur in some parts of the furnace. In operation, the air supplied to the furnace will in the usual manner enter the same 50 through the ash-pit door, a considerable quantity thereof sweeping upwardly and rearwardly through the fuel body and through the passages 17 into the combustion chamber. A quantity of air, however, 55 passes into the conduits 22, being drawn therethrough by the natural draft of the furnace, which has a tendency to draw air from the outlets 33 through the upper part of the fire-box and through the open passages 18 leading into the combustion chamber. The flow of air through the air heating appliance is considerably augmented by the effect of the heat on the air therein. The heated air which is delivered through 60 65 the outlets 33, together with the gases arising

from the fuel body, may be further heated when traveling through the passages in arch 15, ignition taking place near the outlets 20 of such passages when the mixture strikes the flame which is emitted from 70 the solid fuel and sweeps rearwardly through the combustion chamber.

The operation of the furnace may be considerably altered from that above described, for instance, the ash-pit door may be more 75 or less closed and the secondary air supply taken through the inlets 27 of conduits 25. Thus the relative quantities of air for the primary and secondary combustion may be proportioned as desired by adjusting the 80 doors 27 and the ash-pit door. For instance, a certain quantity of air may be entering the furnace through the ash-pit door, some of it passing through the grate and the solid fuel, while some of it enters the vertical 85 conduits 22, while the additional supply of air for the air heating appliance may be entering the same through the inlet 27, according to the adjustment of door 28. In the normal operation of the furnace, the 90 doors 28 and 31 may be closed. These doors also provide means for inspecting the conduits 25 and 29 and cleaning the same if necessary.

Although but one specific embodiment of 95 this invention has been herein shown and described, it will be understood that numerous details of the construction shown may be altered or omitted without departing from the spirit of this invention as defined 100 by the following claims.

I claim:

1. A furnace, comprising surrounding walls forming an ash-pit, a fire-box and a combustion chamber at the rear thereof, a 105 boiler extending along the upper part of said fire-box and combustion chamber, an air heating conduit leading upwardly from the ash-pit to the upper part of said fire-box and from there extending rearwardly 110 along said boiler into the combustion chamber and returning from the combustion chamber into the fire-box, said conduit having an inlet and an outlet respectively in the ash-pit and fire-box, said conduit also having a branch extending through the wall of the furnace to the exterior thereof, and means for regulating the flow of air through 115 said branch.

2. A furnace, comprising surrounding 120 walls forming an ash-pit, a fire-box and a combustion chamber at the rear thereof, an air heating conduit leading upwardly from the ash-pit to the upper part of said fire-box and from there extending rearwardly into 125 the combustion chamber and returning from the combustion chamber into the fire-box, said conduit having an inlet and an outlet respectively in the ash-pit and fire-box, said conduit also having a branch extending 130

through the wall of the furnace to the exterior thereof, and means for regulating the flow of air through said branch.

3. A furnace, comprising surrounding walls forming an ash-pit, a fire-box and a combustion chamber at the rear thereof, an air heating conduit leading upwardly from the ash-pit to the upper part of said fire-box and from there extending rearwardly into the combustion chamber and returning from the combustion chamber into the fire-box,

said conduit having an inlet and an outlet respectively in the ash-pit and fire-box, said conduit also having a branch extending through the wall of the furnace to the exterior thereof, in both the ingoing and outgoing portions thereof, and means for regulating the flow of air through said branches. 15

Signed at Chicago this 25th day of January, 1917.

IRA W. FOLTZ.
